Edmond Opler, Hinsdale, Ill., assignor to World's Finest Chocolate, Inc., Chicago, Ill., a corporation of Illinois

Application September 13, 1952, Serial No. 21,448

Term of patent 14 years

(Cl. D82—2)

To all whom it may concern:

Be it known that I, Edmond Opler, a citizen of the United States, residing at Hinsdale, in the county of Du Page and State of Illinois, have invented a new, original, and ornamental Design for a Candy Bar or Similar Article, of which the following is a specification, reference being had to the accompanying drawing, forming a part thereof.

Fig. 2 is a side elevational view of the candy bar shown in Fig. 1;

Fig. 3 is a top plan view;

Fig. 4 is a cross-sectional view thereof taken on the line 4—4 of Fig. 1; and

Fig. 5 is an end elevational view.

I claim:
The ornamental design for a candy bar or similar article, substantially as shown.

EDMOND OPLER.
